LEO FLIER, OF NEW YORK, N. Y., ASSIGNOR TO THE UNIVERSAL JEWELRY CASE COMPANY, A COPARTNERSHIP COMPOSED OF LEO FLIER AND JOSHUA ZELMAN, BOTH OF BROOKLYN, NEW YORK

WATCH BOX

Application filed August 2, 1928. Serial No. 296,986.

This invention relates to containers for articles of jewelry, and has particular reference to a box for displaying and packaging wrist watches.

The invention primarily contemplates a display watch box which is designed as an all purpose wrist watch box for displaying and packaging ladies' or gentlemen's wrist watches irrespective of whether they are provided with flexible bracelets, ribbons, straps or other types of wrist encircling elements.

More specifically, the invention comprehends in a box for displaying and packaging various types of wrist watches, a panel upon 15 one face of which the watch is placed in substantially flat contact and around which the wrist encircling element is arranged, together with a box body having a depression for accommodating the wrist encircling 20 element of the watch when the same mounted on the panel is laid in flat contact with the upper surface of the box body.

As a further object, the invention embodies in a box of the character set forth a 25 slotted portion in the upper wall of the box body for the reception of an end of the panel whereby the same may be disposed in an angular display position.

Other objects reside in the simplicity of 30 construction and mode of use of the box, the economy with which it may be produced and the general efficiency derived therefrom.

With the above recited and other objects in view, reference is had to the following description and accompanying drawings, in 35 which there is exhibited one example or embodiment of the invention, while the claims define the actual scope of the same.

In the drawings: 40 Figure 1 is a perspective view illustrating the box opened with the watch supporting panel in display position.

Figure 2 is a sectional view therethrough taken approximately on the line indicated at 45 2-2 in Figure 1.

Figure 3 is a similar view with the watch supporting panel disposed in flat contact and with the box cover closed.

Figure 4 is a plan view with the cover 50 open and in section and with the portions of

the box body broken away to disclose the underlying structure.

Referring to the drawings by characters of reference, the box body includes a base or bottom wall 5 and a top wall 6 which is vertically spaced therefrom and supported by marginal walls 7. The top wall is provided with a rectangular substantially central cutout portion 8. A substantially box shaped member 9 equal in length to and of lesser width than the cutout portion 8 and open at its upper end is arranged within the body with the end marginal walls in contact with the end edges of the cutout portion 8 and with one side marginal wall 11 in contact with one side edge of the cutout portion 8 to provide a depression 12 extending downwardly from the upper wall of the box body and to define a slot 13 between the remaining side marginal wall 14 of the member 9 and the remaining side edge of the cutout portion 8. Preferably, a filler element 15 is arranged on the upper surface of the bottom wall 5 between the marginal wall 7 of the box body and the side marginal wall 14 of the member 9. A panel 16, preferably covered with plush 17, is designed for the purpose of supporting the wrist watch which includes the case A and the wrist encircling element B. The box body may be provided with a suitable cover 18 adapted to telescope the box body and preferably hingedly connected thereto at 19.

In use, the case A of the watch is arranged in substantially flat contact with one surface in the panel 16 while the wrist encircling element is trained around the panel to properly associate the wrist watch therewith. To display the watch, the lower end of the panel 17 is inserted through the slot 13 in such a manner as to dispose the panel in a rearwardly and upwardly inclined position, as illustrated in Figures 1 and 2. Certain types of watches, such as small ladies' wrist watches having ribbons or flexible bracelets, may remain on the panel when in display position while the cover is closed. In other types of watches, such as men's wrist watches with heavy straps, the cover cannot be closed while the panel is in display position. In this type

of watch, the panel is removed from the slotted portion and laid flat on the upper wall 6 of the box body, the depression 12 affording room for the reception of the strap, as clearly illustrated in Figure 3.

From the foregoing, it will thus be seen that a watch box for displaying and packaging wrist watches of practically any type has been devised to eliminate the necessity of a jeweler being required to maintain a supply 19 of various sizes of watch boxes for the various types of wrist watches.

What is claimed is:

1. In a box for displaying and packaging 15 wrist watches, a panel upon one face of which the watch is placed and around which the wrist encircling element is arranged, a box body having an upper wall provided with a depression for accommodating the wrist encircling element of the watch when the same 20 mounted on the panel is laid flat upon the upper wall of the box body and a slotted portion in the upper wall of the box body in which the end of the panel is engageable for 25 disposing the same in an angular display position.

2. In a box for displaying and packaging 30 wrist watches mounted on a display panel around which the wrist watch encircling element is arranged, a box body having a slotted 35 upper wall for receiving and holding the panel in an angular display position and having a depression for receiving the wrist encircling element when the panel is arranged in flat contact therewith, whereby a cover 40 may be fitted thereover without materially increasing the overall depth of the box.

3. In a box for packaging and displaying 35 wrist watches, the combination with a display panel around which the wrist encircling element of the watch is arranged, of a box body having an upper wall formed with a cutout portion, a box shaped member equal 40 in length to the length of the cutout portion and of lesser width than the same and open at its upper end arranged within the box body with the end marginal walls in contact with the end edges of the cutout portion and with one side marginal wall in contact with one side edge of the cutout portion to provide a depression within the member extending downwardly from the upper wall of the box body, said member, together with the 45 cutout portion, defining a slot as and for the purpose specified.

4. A box for displaying and packaging 50 wrist watches comprising a body having a telescopically associated cover, said body including a top wall, a bottom wall and depending marginal walls, the top wall having a rectangular cutout portion and means subdividing the box body vertically and longitudinally to define in alignment with the cutout portion and communicating therewith a depres-

sion and a slotted portion as and for the purpose specified.

Signed at Brooklyn, in the county of Kings and State of New York, this 20th day of July, A. D. 1928.

LEO FPLIER.
